Act

United States Patent Office.

MILTON BRADLEY, OF SPRINGFIELD, MASSACHUSETTS, ASSIGNOR TO THE UNION MANUFACTURING COMPANY, OF NEW BRITAIN, CONNECTICUT.

Design No. 3,664, dated September 21, 1869.

DESIGN FOR A HINGE.

The Schedule referred to in these Letters Patent and making part of the same.

To all whom it may concern:

Be it known that I, MILTON BRADLEY, of Springfield, in the county of Hampden, and State of Massachusetts, have invented a new Design for Hinge; and I do hereby declare the following, when taken in connection with the accompanying illustration, to be a full, clear, and exact description of the same, and which said illustration constitutes part of this specification, and represents a view of the hinge, open.

This invention relates to a design for that class of hinges which is ornamented upon its meeting-surfaces.

The hinge-plates are finished with a plain or moulded edge, within which the tracery or ornamentation of my

design is placed. Such edge, however, constitutes no part of the present design, my design consisting of the peculiar configuration of the tracery on the hinge-plates, irrespective of the finish of the edge, which is fully represented in the accompanying photographic illustration, to which reference is made.

I claim, as my invention, the design for hinge-plates, as described and shown.

MILTON BRADLEY.

Witnesses:
